Inventor:
Fred Willis Gunn

To Harry D. Thomson
Attest.

UNITED STATES PATENT OFFICE.

FRED WILLIS GUNN, OF BOSTON, MASSACHUSETTS.

HOSE-CLAMPING TOOL.

Application filed August 8, 1921. Serial No. 490,582.

To all whom it may concern:

Be it known that I, FRED WILLIS GUNN, a citizen of the United States of America, residing at Boston, in the county of Suffolk and State of Massachusetts, have invented new and useful Improvements in Hose-Clamping Tools, of which the following is a specification.

This invention relates to tools for manipulating and applying bands or wires, and while having other and more general fields of usefulness, is well adapted and designed for applying clamping bands or wires to hose or like flexible tubes for clamping and securing the same to pipes, nozzles, couplings and the like.

A principal object of the invention is to provide a simple and easily operated tool that is adapted to first draw up a clamping band or wire tightly around the hose, and then to sever it, leaving a proper length of the wire end projecting and substantially bent back so that the clamp is secure as the tool is removed. A further object is to provide a tool of the kind described with improved means for removing the wire extremities that are caught in the device after an operative movement thereof. The foregoing and other objects of the invention will more fully appear from the following detailed description, and the distinctive features of novelty will be pointed out in the appended claims.

Referring to the drawings:—

Figure 1 is a side elevation of a tool embodying the invention; Fig. 2 is an edge view thereof; and Fig. 3 is a longitudinal sectional view. 10 indicates the body of the tool comprising a head 10^a and a handle portion 10^b. The head portion 10^a is formed with a transverse bore 11 in which a pin 12 is fitted to turn. The head 10^a has a longitudinal passage 13 therethrough of a dimension to receive one end portion of a band or wire B which is to be used for clamping the hose H. The inner portion of the pin 12, opposite the passage 13 is cut away for approximately half the diameter thereof presenting a flat side 14 which is in alignment with the inner side of the passage 13. The pin 12 has rigid therewith a handle 15 projecting at a small angle with reference to the handle portion 10^b of the body so that it may be readily grasped for turning the pin to sever the band as now to be described.

The outer edge of the plain face 14 of the pin thus constitutes a cutting or shearing edge in co-operation with the side of the passage 13 so that when an extremity B' of the hose band B has been drawn taut through the passage 13, it may be severed by manipulating the handle 15 to turn the pin 12 in a reverse clockwise direction as seen in Figure 2. For first drawing the band extremity up taut so as to clamp the hose properly, a pin 16 is mounted transversely in the body 10 a small distance outward from the pin 12. This pin 16 is formed with a passage 17 therethrough which in one position of said pin is adapted to receive the band extremity B therethrough as seen in Fig. 3. The pin 16 is equipped with suitable means for turning the same, this being shown as a hexagonal head 18 at one end thereof and at the side of the tool, adapted to receive a wrench or the like for operating the same.

The front of the head 10^a is beveled off directly in front of the passage 13 as indicated at 19. The purpose of this bevel is so that after the band is drawn taut and clamped properly around the hose by the turning of the pin 16 with the band extremity therethrough, the body of the tool may be swung downward from the position indicated in Fig. 3, thereby bending the band extremity B' backward at a substantially acute angle around the loop L of the clamp, whereby the clamp band will be secure upon removal of the tool.

After the tool has been operating as described, it will be understood that a portion of the severed extremity of the band will be wound around the pin 16. For disengaging this extremity, a cutter member 20 is provided pivoted within the body at 21 and adapted to be swung upward to the dotted line position indicated in Fig. 3 so that its edge at 20^a engages the periphery of the pin 16. Then upon turning the pin in a clockwise direction as indicated in Fig. 3, the wire extremity will be severed and may be readily removed. The pins 12 and 16 may be detachably assembled with the body of the tool and held by suitable cotter pins 22. I am aware that the invention may be embodied in other specific forms without departing from the spirit or essential attributes thereof, and I therefore desire the present embodiment to be considered in all respects as illustrative and not restrictive, reference

being had to the appended claims rather than to the foregoing description to indicate the scope of the invention.

Having described my invention, what I claim as new and desire to secure by Letters Patent is:

1. A hose clamping tool comprising a body having a head integrally formed at one end thereof with a longitudinal passage 10 for receiving a clamping band or wire, a member mounted to turn in said head and co-operative therewith for severing the band, and means co-operative with said head for drawing the band taut preliminary to 15 the severance thereof.

2. A hose clamping tool comprising a body having a head integrally formed at one end thereof with a longitudinal passage to receive a clamping band, a pin 20 mounted to turn in the body equipped to engage the extremity of the band to draw the same taut, and means mounted in the head and co-operative therewith for severing the band.

25 3. A hose clamping tool comprising a body having a head integrally formed at one end thereof with a passage therethrough to receive a clamping band, and with a beveled face in front of said passage, means 30 borne by the body for drawing the band taut, and a pin mounted to turn in said head equipped for co-operation with the head to sever the band.

4. A hose clamping tool comprising a body having a head integrally formed at one end thereof, with a passage therethrough to receive a clamping band or wire, a pin mounted to turn in the body equipped 35 to engage the extremity of the band to draw

the same taut, a pin mounted to turn in the 40 head having an operating handle and equipped with an edge co-operative with the head to shear off the band, and means co-operative with the first named pin for clearing the band extremity therefrom. 45

5. A hose clamping tool, comprising a body having a head integrally formed at one end thereof with a passage therethrough to receive a clamping band or wire, said head being provided with a transverse passage, with the first mentioned passage opening into the transverse passage, a pin mounted to turn in the last mentioned passage and provided with a diametrically disposed passage in line with the first mentioned passage in the head and adapted to receive one end of the band, a second pin mounted for rotation in the body and provided with a passage adapted to align with the first mentioned passage in the head and the diametrically disposed passage in the first mentioned pin, said last mentioned pin being adapted to be operated for drawing the wire taut, a handle operatively connected with the first mentioned pin for rotating the pin in the second mentioned passage in the head for causing the first mentioned passage in the head and the diametrically disposed passage in the pin to be moved out of alignment, whereby the clamping band is sheared. 50 55 60 65 70

In testimony whereof I affix my signature in presence of two witnesses.

FRED WILLIS GUNN.
